UNITED STATES PATENT OFFICE.

WILLIAM ESCHEMANN, OF PHILADELPHIA, PENNSYLVANIA, ASSIGNOR OF
ONE-THIRD TO GEORGE W. KOCH, OF SAME PLACE.

DESIGN FOR AN INDICATOR-LEVER FOR LETTER-SCALES.

SPECIFICATION forming part of Design No. 31,582, dated October 3, 1899.

Application filed March 13, 1899. Serial No. 703,961. Term of patent 7 years.

To all whom it may concern:

Be it known that I, WILLIAM ESCHEMANN, a citizen of the United States, and a resident of Philadelphia, Pennsylvania, have invented or produced a new and original Design for Indicator-Levers for Letter-Scales, of which the following is a specification.

My design is fully shown in the accompanying drawing, which represents a perspective view of the indicator-lever.

The essential features of the design are a central boss or hub with three arms projecting therefrom, the end of one arm being bent over and folded back upon itself, so as to form a pointer.

In the drawing, 1 represents the central boss or hub, and 2, 3, and 4 the arms projecting therefrom, 5 representing the bent or

folded end of the arm 4, which constitutes the pointer. The boss or hub 1 has a central opening 6. The arm 2 has an opening 7 near its outer end, and the arm 3 has a similar opening 8.

Having thus described my invention, I claim and desire to secure by Letters Patent--

The design for an indicator-lever for a letter-scale, as herein described and shown.

In testimony whereof I have signed my name to this specification in the presence of two subscribing witnesses.

WILLIAM ESCHEMANN.
